Primary Examiner — Omeed Agilee*Assistant Examiner* — David Truong(74) *Attorney, Agent, or Firm* — David M. Stein(57) **CLAIM**

The ornamental design for a water rower, as shown and described.

DESCRIPTION

FIG. 1 is a right perspective view of a water rower showing the new design.

FIG. 2 is a rear view thereof.

FIG. 3 is a front view thereof.

FIG. 4 is a left side view thereof; and,

FIG. 5 is a right side view thereof.

The broken lines in the drawings depict portions of the water rower that form no part of the claimed design.
